Claims priority, application Sweden
December 12, 1949

9 Claims. (Cl. 18—15)

1

This invention relates to the art of producing absorbing or sponge material from a cellulose ester such as cellulose xanthate or viscose. The invention is particularly concerned with the production of sponge cloth and an object is to provide a method and an apparatus which will be continuous in their operation and will produce a sponge sheet of desired thickness for sponge cloths having the requisite strength and other desired properties. Other objects of the invention are economy in production, simplicity and reliability in operation, and uniformity of product.

Artificial sponge material is commonly made by the intimate mixture of a pore-forming substance, such as sodium sulphate decahydrate or Glauber's salt with viscose, followed by coagulation and the customary after treatments, the sponge material frequently being molded into the desired final form. The salt dissolves and incidentally coagulates the adjacent viscose, thereby forming cavities or pores in the body of the material. It is also customary to augment the inherent strength of the product by the incorporation of a fibrous material into the product. For example, cotton or hemp fibers are commonly added to the intimate mixture without any control as to their directional dispositions and consequently the fibers lie in all directions. If a block of such sponge material is cut into thin sheets or layers a sponge cloth is obtained. However, as the fibers in a cloth produced in this manner are not oriented in the plane of the cloth only, the strength is not so high as would be the case if the longitudinal disposition of the fibers was confined to the plane of the cloth.

Due to the thickness of the original sponge material from which sponge cloths may thus be cut, a considerable time is required to effect coagulation throughout and consequently it is difficult to produce such material by a continuous operation.

These disadvantages are obviated by this invention which contemplates the formation of a sheet of the proper thickness for sponge cloths by a continuous operation which includes a control that effects the orientation of the fibers in the plane of the cloth in both a transverse and longitudinal direction, thus strengthening the sheet in both dimensions.

More particularly in accordance with the method the intimate mixture of viscose, Glauber's salt and fibers is deposited upon a traveling belt and is spread out evenly and is subjected to both transverse and longitudinal surface rubbing or

agitation which tends to orient the fibers in those respective directions.

This method makes possible the production of a thin layer or sheet of the material having the thickness of the desired cloth product with the consequent rapid coagulation throughout its thickness and hence the possible continuous operation. Moreover because of the quick coagulation weakening of the material is avoided which results from the prolonged immersion in the hot coagulation bath usually required in the production of artificial sponge material.

In order to make the sponge cloth more pliable and supple, it may have a surface pattern imparted to it by providing the belt with a complementary pattern. If it is desired to form a pattern on the upper sides of the cloth, this may be done by subjecting that surface to pressure by a mold device such as a roller having the desired surface design, in advance of the coagulation. Either or both of such patterning procedures may be used on the traveling web.

As an apparatus the invention contemplates an endless belt of a material resistant to the chemicals in the viscose solution and in the coagulating bath and an extrusion press such as a screw conveyor for discharging the mass upon the belt, with means to drive the belt and to direct it into and out of a coagulating bath. To spread the mass at the proper thickness and to orient the fibers in the plane of the web more or less in a direction transverse to the travel of the belt, a spreader is laterally reciprocated over the belt at the proper distance therefrom and in a position after the extrusion press. Following the reciprocating spreader is a surface contacting device having continuous relative movement in the direction of travel of the web. Acceptably such a device may be a roller properly spaced from the belt and rotating at a peripheral speed exceeding the speed of the belt and in the same direction as the belt.

Other features and advantages of the invention will appear from the following description of the construction and operation of the apparatus shown by way of illustration in the accompanying drawing.

The mass used for the production of the sponge is poured into the hopper of a screw press 1 and is discharged by said press as a string on to an endless belt 2 which is preferably patterned and made of rubber. The mass is spread by an arm 3 swinging back and forth in the transverse direction, whereby the material is spread according as it passes along the belt, so that when

leaving the swinging sector of the arm 3, it has obtained the desired thickness. The thickness of the mass is determined by adjusting the height of the arm above the surface of the belt.

The mass now follows the belt and the fibers of the mass will preferably become oriented in the transverse direction, for which reason the web of mass, if not further mechanically treated, would become stronger in the transverse direction than in the longitudinal direction. However, due to the fact that a roller 4, which rotates at a peripheral speed which is greater than the traveling speed of the mass and of the belt, is located in such a manner that it presses the mass against the belt, some of the fibers will change their position so as to be oriented in the longitudinal direction. By adjusting the speed and the pressure of this roller, any desired number of fibers can be directed parallel with the longitudinal direction of the belt.

Due to the above possibilities of combination it has appeared in practice that the same strength can be obtained in the longitudinal as well as in the transverse direction of the sponge cloth, and as the fibers now lie in these two directions and naturally to a certain extent also in other directions in the plane of the web of mass, the strength becomes considerably higher than in a sponge cloth cut from a block.

The belt 2 then conducts the mass into a coagulation bath 5, which simply may consist of a hot (i. e. heated to about the boiling point) solution of sodium sulphate. During its passage through the bath the mass coagulates, and after having passed a roller 6 in the bath, the sponge cloth now formed is continuously drawn off from the belt 2 at a roller 7 outside the coagulation bath. The cloth 8 thus obtained is then subjected to further chemical treatment, i. e. desulphurising, bleaching and so on, and is dried.

Before new mass can be discharged on the rubber belt 2, said belt should be cooled and brushed clean, which is done in a bath 9, consisting of cool water and possibly containing certain chemicals which prevent the mass when subjected to the subsequent coagulation, from adhering so tightly to the belt that the mass cannot be easily drawn off at the roller 7. The brushing is preferably carried out with brushes 10 operating in the cooling bath.

It will be appreciated that an incidental advantage of forming the sheet on the conveyor belt is that the belt forms a reinforcing support for the nascent sheet through the hot liquor until the coagulation is effected and thus makes possible the continuous sheet formation at high operating speed with minimum likelihood of rupture.

The belt is guided over a roller after the separation of the web into the bath 9 through which it is guided by two rollers and thence over a roller 60 on the level at which the material is deposited, which latter roller is power driven and drives the belt.

It will be understood that the particular apparatus shown in the drawing and above described is illustrative only and that the invention defined in the following claims may be variously otherwise embodied.

What is claimed is:

1. The method of producing a continuous sheet of absorbing material consisting in depositing an intimate mixture of viscose, salt crystals and fibers in a continuous stream on an endless traveling belt, subjecting the deposited material on the belt to a surface rubbing action in a certain

direction in the plane of the belt sufficient to orient a substantial portion of the fibers in the direction of rubbing, then subjecting the deposited material on the belt to a second surface rubbing in a direction at a substantial angle to the first rubbing sufficient to orient a substantial portion of the fibers in the last mentioned direction conveying the web on the belt after the rubbing treatment through a coagulating bath, and then separating the sheet so formed from the belt.

2. The method of producing a continuous sheet of absorbing material consisting in depositing an intimate mixture of viscose, salt crystals and fibers in a continuous stream on an endless traveling belt, subjecting the deposited mixture to a laterally reciprocatory spreading action, thereby orienting some of the fibers in a transverse direction, conveying the mixture on the belt following such action through a coagulating bath, and then separating the sheet so formed from the belt.

3. The method of producing a continuous sheet of absorbing material consisting in depositing an intimate mixture of viscose, salt crystals and fibers in a continuous stream on an endless traveling belt, subjecting the deposited mixture to a laterally reciprocatory spreading action and thereby spreading it evenly on the belt and orienting some of the fibers in a transverse direction, subjecting the sheet so formed to a forwardly moving rubbing action sufficient to orient some of the fibers in a longitudinal direction, conveying the sheet so treated on the belt through a hot coagulating bath, and then separating the sheet from the belt.

4. A method as claimed in claim 3 together with the step of molding a pattern in a surface of the sheet while on the belt.

5. An apparatus for producing a continuous sheet of absorbing material comprising a driven endless belt, means for guiding the belt through a coagulating bath, means for guiding the belt through a cooling bath, means to deposit a continuous stream of viscose on the belt, means for spreading the deposited material located adjacent the material depositing means and disposed over and spaced from the belt by the thickness of the web to be formed, and means for reciprocating said spreading means in a direction transverse to the movement of the belt.

6. An apparatus for producing a continuous sheet of absorbing material comprising a driven endless belt, a coagulating bath, a cooling bath, means to guide the belt successively through said baths, means for depositing a continuous stream of viscose on the belt, a spreader for the material spaced from the belt the thickness of the sheet and disposed between the said means and the coagulating bath, a rotatable roller disposed transversely over the belt between the spreader and coagulating bath in position to engage a sheet of the material and means capable of rotating the roller in the direction of movement of the belt at a peripheral speed exceeding the speed of the belt.

7. An apparatus for producing a continuous sheet of absorbing material comprising a driven endless belt, a coagulating bath, a cooling bath, means to guide the belt successively through said baths, means for depositing a continuous stream of viscose on the belt, transversely reciprocatory spreading means adjacent the material depositing means and disposed over and spaced from the belt by the thickness of the sheet to be formed, a rotatable roller disposed transversely over the belt between the spreader and coagulating bath in

position to engage a sheet of the material and means capable of rotating the roller in the direction of movement of the belt at a peripheral speed exceeding the speed of the belt.

8. The method of producing a continuous sheet of absorbing material consisting in depositing an intimate mixture of viscose, salt crystals and fibers in a continuous stream on an endless traveling belt, subjecting the deposited mixture on the belt to a laterally reciprocatory spreading action to orient some of the fibers in a transverse direction, conveying the mixture on the belt after such spreading through a coagulating bath and separating the sheet so formed from the belt.

9. The process of claim 8 wherein a belt having a patterned surface is employed and such pattern

is molded into the surface of the sheet in contact with the belt.
